UNITED STATES PATENT OFFICE.

ALVAH K. ALLEN, OF KANSAS CITY, MISSOURI.

COLLAPSIBLE TOWER.

Application filed June 29, 1927. Serial No. 202,305.

This invention relates to new and useful improvements in towers, and particularly to collapsible towers.

One object of the invention is to provide a tower which is capable of being elevated to a great height to permit persons to escape from the upper stories of a burning building.

Another object is to provide a device of this character which is capable of being rotated so that it may be properly positioned with relation to the windows of the building, regardless of the position of the base of the tower, in the street below.

A further object is to provide bridges or runways, on the upper end of the tower, which may be readily thrown out to the windows of the building, for the persons to escape from the building.

A further object is to provide novel means for bracing the tower after the same has been elevated, whereby to prevent collapse thereof.

Other objects and advantages will be apparent from the following description when taken in connection with the accompanying drawings.

In the drawings:

Figure 1 is a side elevation of the tower in partly elevated position.

Figure 2 is a top plan view of the same.

Figure 3 is a vertical sectional view through the upper portion of the tower, on the line 3—3 of Figure 2, one of the bridges being in extended position.

Figure 4 is a horizontal sectional view on the line 4—4 of Figure 1, showing the operating mechanism at the base of the tower.

Figure 5 is a vertical sectional detail view through one of the drums 34, on the line 5—5 of Figure 2.

Figure 6 is a vertical sectional detail view on the line 6—6 of Figure 2.

Figure 7 is a horizontal sectional view on the line 7—7 of Figure 6.

Referring particularly to the accompanying drawings, 10 represents a wheeled support, which is in the form of a portable truck. Supported on the truck is a turntable 11, and supported on said turntable is the lower end of the tower, represented as a whole by the numeral 12. This tower is in the form of lazy-tongs, and includes the beams 13, which are secured to the turntable, and to one side of the lower end of the tower, and the sliding beams 14, which are secured to the other side of the lower end of the tower, for movement longitudinally past the beams 13. These

beams 13 and 14 are secured respectively to the transverse beams 15 and 16, forming a part of the lower end of the tower. In the beam 15 there is formed an opening, and secured to the beam outwardly of the opening is an internally threaded member 17. The beam 16 is also formed with a central opening, and secured in covering relation thereto is a centrally apertured plate 18. Swiveled in the plate 18 is a threaded rod 19, the other end of which is screwed into the member 17, the first named end of said rod being provided with a crank handle 20 by means of which the rod may be rotated, for the purpose of elevating and lowering the lazy-tongs. Upon rotating the rod 19 in one direction, the beams 15 and 16 will be drawn toward each other, with the result that the elements of the lazy-tongs will be actuated to rise above the truck, and upon rotation of the rod in the opposite direction such beams will be moved away from each other whereby to cause the collapse of the lazy-tongs, and the lowering of the tower. On the inner faces of the side members 22, of the lazy-tongs are grooved wheels 23, and engaged with said wheels are the cables 24, the lower ends of which are secured to, and arranged to be wound on the shaft 25, mounted in the turntable. A crank handle is provided on one end of the shaft 25, for the purpose of turning the same to render the cables taut or loose, as the occasion may require. When in taut condition the cables serve to properly brace the elements of the lazy-tongs, and hold the same against accidental collapse. These cables may, however, be used to elevate the tower, if desired, irrespective of the screw rod 19.

On the upper end of the tower is a platform 26, and slidably on each end of the platform is a bridge 27. Each bridge has collapsible side rails 28, and connected to the inner end of each side rail is one end of a cable 29, the other end of which passes downwardly through an opening 30, in the platform, around a pulley 31, and is connected with a vertical rotatable shaft 32. A handle or wheel 33 is mounted on the upper end of the shaft 32, whereby such shaft may be rotated to draw up on the cables, and more properly support the bridge in its extended position. Mounted on the platform are two winding drums 34 and 35, and wound in opposite directions on each drum are cables 36 and 37. The other end of the cable 36 is secured to the outer end of the

bridge, while the other end of the cable 37 is secured to the inner end of the bridge. Upon rotating the drum in one direction, the cable 37 will be wound onto the drum with the result that the bridge will be forced outwardly, while the slack in the cable 36 will be taken up by the pull exerted thereon by the outer end of the bridge. Thus, while the cable 37 is being wound on to the drum, the cable 36 10 is being unwound therefrom. After the bridges have been run out to the desired length, and are properly positioned to receive persons escaping from a building, through a window, the fireman, on the platform turns 15 the hand-wheel 33 to render the cables 29 taut, so that the bridge will be more securely held in horizontal position, for supporting the weight of the persons passing thereover.

A frame 38 is erected on the intermediate 20 portion of the platform, and secured to the upper portion of this frame are pulleys 39, over which pass the ropes 40 and 41, the former of which carries a basket, into which the escaping persons enter to be lowered down 25 through the center of the tower, to the ground. The other cable is adapted to be used for elevating or drawing the nozzle of a hose up to the platform for use by the fireman, to direct a stream of water onto the burning building. It will be understood that chemical 30 apparatus may also be carried on the platform, so that the fireman may enter an upper story of a building and use the same on a fire which might be too small to require the employment of the hose.

While I have shown the rod 19 for raising

and lowering the tower, it will be understood that any other means may be employed, such as an hydraulic mechanism, an electric or gas motor, or the like.

Any suitable means may be employed for rotating the turntable, such as the worm gear 42, illustrated in the drawings, or a motor may be used to rotate the same.

While I have shown and described the tower as adapted for use in connection with fire apparatuses, I wish it understood that the tower may be used advantageously as a fruit picking scaffold, as a painter's scaffold, or as a folding ladder for various purposes requiring the reaching of great heights.

What is claimed is:

In a fire tower, the combination with the platform thereof, of a bridge including a runway slidably supported by the platform, 55 an upright on the platform, hand-rails on the bridge runway adapted to collapse when the runway is withdrawn, a cable connected with the said upright and extending along and connected with the upper portion of each hand-rail, means for extending and withdrawing the bridge, a vertically disposed drum on the platform adjacent the inner end of each hand-rail, a ratchet winding staff associated with each drum, and a cable connected with the upper portion of the inner end of each of the hand-rails and with a drum and arranged 60 to be wound on said drum whereby to perform the actions of a guy for maintaining the bridge rigidly in extended portion.

In testimony whereof, I affix my signature.

ALVAH K. ALLEN.
